SLUG CONTROL GUIDE FOR SLUG CASTING MACHINES

Harold O. Mohr, Marengo, Ill., assignor to Mohr Lino-Saw Company, Skokie, Ill., a corporation of Illinois

Application July 25, 1958, Serial No. 751,022

9 Claims. (Cl. 199—61)

The present invention relates to an improved slug control guide for slug casting machines. The invention has its principal field of utility in connection with slug casting and sawing machines provided with a rotary saw for cutting the cast type slugs, but the invention is not necessarily limited to use with these slug sawing machines. These slug sawing machines are constructed in the form of attachment units adapted for mounting on type casting machines, such as the well-known "Linotype" and "Intertype" linecasting machines. This slug sawing attachment unit is known in the trade as the "Mohr Saw," and is exemplified in prior Patents 1,264,541, 1,358,972 and 2,563,147.

The present invention relates to an improved upper control guide for maintaining a guiding and controlling engagement with the upper ends of the type slugs as they pass between the vise frame and knife block in their travel from the mold wheel of the linecasting machine to the rotary saw of the Mohr slug sawing unit.

Heretofore, these upper control guides have been in the form of one or more thin sheet metal leaves having anchored attachment at one end to the upper knife block liner, and having their other or free ends vertically flexible for exerting a resilient downward pressure upon the upper ends of the type slugs as the type slugs pass below the control guide. These prior leaf spring guides have been subject to several objections.

For example, in attempting to secure completely satisfactory delivery of slugs in a given range of thickness, these prior leaf springs require laborious and painstaking adjust-and-try adjusting operations; and these have to be redone whenever the typesetting machine is called upon to produce slugs having a different range of type sizes and slug thicknesses.

Still another objection arises because the range of flexure and the angles of flexure of these control guides vary considerably, and after a moderate degree of usage, the metallic composition of these leaf spring guides tends to crystallize or fatigue, with resultant cracking or breakage. Furthermore, these prior leaf spring guides have been so mounted that after they have thus become broken or cracked, it is a very laborious, time consuming job to replace them. Also, these prior leaf spring guides do not impose a constant or uniform downward guiding pressure upon the upper ends of the type slugs; but to the contrary, the pressure varies from point to point along the lengths of these prior leaf spring guides. Moreover, these prior leaf spring guides have not had the requisite effectiveness for exerting a desired lateral or sidewise pressure upon the ends of type slugs. This sidewise pressure is particularly desirable for holding type slugs that

2

carry characters which overhang the solid part of the type slug pressed laterally against the stationary vertical wall of the vise frame, in order that these slugs will be firmly guided between the vise frame and knife block so that the ejector blade of the linecasting machine will not slip into a non-pushing position alongside the slug and thus fail to eject the slug. Slugs of this latter type usually have relatively wide type characters which overhang the narrower solid slug which forms their base, as exemplified for the make-up of grocery store advertisements. Such slugs, without firm guidance, have a tendency, because of their unbalanced configuration, to twist as they are pushed forward through the knife block, thereby allowing the ejector blade to slip into a non-pushing position alongside the slug, so that the ejector blade is unable to complete the ejection of the slug.

All of the foregoing objections to the old metallic leaf spring guides have been avoided in my improved construction of control guide herein disclosed. Instead of relying upon a metallic leaf spring construction for obtaining resilience, I utilize one of the elastomeric materials, such as neoprene, which has a much greater degree and range of resiliency, and which also has a longer life. This elastomeric material is embodied in a horizontal layer, and adhering to the lower side thereof is a relatively thin metallic slide plate with which the upper ends of the type slugs have sliding contact of minimum friction. This cushioning layer of elastomeric material exerts a constant or uniform downward pressure against the type slug throughout the entire length of the guide from end to end thereof. Also, this cushioning layer of elastomeric material is very effective for exerting a lateral or sidewise pressure in a diagonally downward direction against the upper ends of slugs of a wide range of thicknesses, and particularly those containing overhanging characters as heretofore described, for the purpose of holding these slugs pressed laterally against the stationary vertical wall of the vise frame in an upright position preparatory to being cut by the rotary saw. Still further, my improved control guide embodies a simplified mounting arrangement, according to which the control guide can be removed for repair or replacement by the simple removal of a readily accessible mounting screw extending horizontally through one end of the mounting plate of the guide.

Other objects, features and advantages of the invention will be more apparent from the following detail description of one preferred embodiment thereof. In the accompanying drawings illustrating such embodiment:

Figure 1 is a vertical fragmentary view showing the relationship of the improved control guide with respect to the mold wheel and to the rotary saw, this view corresponding approximately to a section taken on the plane of the line 1—1 of Figure 2.

Figure 2 is a horizontal sectional view taken approximately on the plane of the line 2—2 of Figure 1.

Figure 3 is a front edge view showing the control guide in end elevation in its relationship to the type slug guide-way defined between the vise frame and knife block.

Figure 4 is an enlarged fragmentary sectional view showing the upper portion of Figure 3.

Figure 5 is a side elevational view of the improved control guide on a larger scale.

Figure 6 is an end elevational view thereof.

Figure 7 is an isometric view of a conventional type slug of ordinary width.

Figure 8 is a similar view of a composite assembly characterized by a type slug having overhanging characters; and

Figures 8A, 8B and 8C are similar views of the different slugs going into the make-up of the composite assembly of Figure 8.

Inasmuch as the linecasting machine and the slug sawing machine are both generally old and well-known, as exemplified in the aforementioned patents, the present application only discloses so much of each machine as is necessary to an understanding of the invention. In Figures 1 and 2 the mold wheel of the linecasting machine is illustrated fragmentarily at 10, this mold wheel having four or more linecasting molds 12 mounted at angularly spaced points around the face of the mold wheel. These casting molds 12 revolve with the mold wheel in an intermittent step by step motion from a molding station (not shown) in the linecasting machine, where the type slugs, indicated at S, are cast against selected type characters, to the slug ejecting station, shown in Figures 1 and 2, where the slugs S are ejected for feeding to the slug sawing attachment, indicated generally at 14. The type slugs S are ejected in a forward horizontal direction from each casting mold 12 at the slug ejecting station by an ejector blade 16 which moves forwardly through the casting mold 12 from the rear side thereof. From the casting mold 12 the ejected type slug S moves forwardly through a horizontally extending guide channel 20, the starting end of which is defined between the cutting edges 22 of two laterally spaced side knives 24, 25 extending vertically parallel to the vertical position of the ejected slug at the ejecting station of the mold wheel. These side knives 24, 25 trim the side surfaces of the type slug of any sprue edges or excess thickness. The left hand side knife 24 is located at the inner end of a vise frame 26, the right hand vertical face 28 of which defines a stationary continuation of the left hand side of the guide channel 20. The right hand side knife 25 is mounted in the inner edge of a knife block 30 which has horizontal shifting movement toward and away from the vise frame 26 to accommodate different thicknesses of type slugs S.

Interposed between the left hand vertical face 32 of the knife block 30 and the right hand vertical face 28 of vise frame 26 is a spring plate 34 which is yieldingly pressed to the left to hold the type slugs S pressed firmly against the vertical face 28 of the vise frame 26. This spring plate 34 has mounting on the knife block 30, and is yieldingly pressed toward the left by a vertically disposed leaf spring 38 which is anchored at its center to the knife block 30 by a screw 40, and which has its upper and lower ends pressing resiliently against the upper and lower portions of the spring plate 34 (Figure 4). The outer or front edge of this spring plate 34 continues almost to the cutting plane of the circular cutting saw 44, at which point the spring plate 34 is formed with a laterally bent flange 46. It will thus be seen that the guide channel 20 which begins at the cutting edges 22 of the side knives 24, 25 continues forwardly between the right hand vertical face 28 of the vise frame 26 and the left hand face 48 of the spring plate 34 substantially to the cutting zone of the circular saw 44, so that the vertically disposed type slug S remains under the guiding influence of the guide channel 20 while the type slug is being forced entirely through the guide channel 20 by the ejector blade 16, the type slug remaining under this guiding influence until the slug sawing operation is started and up until the time that it is almost completed. The spring plate 34 yields resiliently toward the right to widen the guide channel 20 as wider type slugs S are ejected from the casting molds 12 of the mold wheel 10.

The cutting saw 44 is a high speed circular saw which is mounted on a vertical drive shaft 48, and the saw 44

and its shaft 48 are arranged for vertical sliding adjustment up and down along the vertical axis of the drive shaft 48. Through the actuation of convenient and quickly operating adjusting mechanism, the operator of the linecasting machine can raise or lower the circular saw 44 to different vertical levels for cutting off greater or lesser amounts of upper portion of each type slug S, depending upon the requirements of the particular type format. After the slug sawing operation, the usable lower portion of the slug is delivered to an assembly platform where the successive slugs are assembled in galley form or upon a galley stick; while the scrap upper portion of the slug is discharged down a waste chute.

The bottom surface of the guide channel 20 is defined by a lower liner 52 (Figures 1 and 3) which is usually secured to the vertical face of the knife block 30. On linecasting machines of "Intertype" manufacture, this lower liner 52 is usually constructed as an integral part of the knife block itself, rather than as a loose part. The lower ends of the type slugs S engage the top surface of this lower liner or guide surface 52 out to approximately the outer end of the guide channel 20, substantially to the point where the type slugs S come into cutting engagement with the cutting saw 44. If desired, the guide surface of this lower liner 52 may have a slight upward slope, or the initial part of this guide surface may have this upward slope.

In the conventional slug sawing machine as heretofore made, the top horizontal edge of the guide channel 20 has been defined by the aforementioned upper leaf spring liner which has been mounted on the underside of a metallic mounting block or mounting body 56. On linecasting machines or "Intertype" manufacture, this mounting body 56 is constructed as a part of the knife block 30; whereas in linecasting machines of "Linotype" manufacture this mounting block 56 has readily detachable mounting on pins 58 projecting laterally from the knife block 30.

All of the above described parts are standard equipment in the conventional linecasting machine (either Intertype or Linotype) and in the conventional slug sawing machine.

Referring now to the improved slug control guide constituting the present invention, this guide is designated 60 in its entirety, and has mounting on the underside of the aforesaid mounting block 56 where it exerts downward resilient pressure against the top edges of the type slugs S as the slugs are advanced through the guide channel 20 from the mold wheel 10 to the cutting saw 44. This improved control guide comprises an upper mounting plate 62, an intermediate layer of elastomeric material 64, and a lower sliding or presser plate 66. The upper mounting plate 62 has a right angle leg 68 bent upwardly at its front end, which has an aperture 70 therein for receiving a mounting screw 72. The mounting block 56 has a tapped hole 74 in its front end for receiving the mounting screw 72. The mounting screw 72 is readily accessible from the front end of the slug sawing machine (i.e., from the front end of the guide channel 20), and by the removal of this mounting screw 72 the entire control guide assembly 60 can be readily removed for substitution or repair. In the mounted position of the control guide the mounting plate 62 is held pressed up against the underside of the mounting block 56, or body 56, or against the underside of any stationary or adjustable upper knife block liner.

The intermediate yieldable layer 64 consists of a strip of an elastomeric or rubbery resilient material having a high degree of resilience or elasticity. For example, I have used with considerable success "Lavell 1/8 inch closed cell neoprene sponge," but it will be understood that other comparable materials may be employed. This neoprene layer 64 has its upper surface secured to the mounting plate 62 and has its lower surface secured to the slide contact plate 66 by cementing, vulcanizing

or in any other suitable manner. The lower slide plate 66 has an upwardly curved beginning end 66' which exerts a resilient downward camming pressure against the top edge of each type slug S as it emerges from the casting mold 12 and enters the guide channel 20, thereby holding the lower edge of the type slug pressed downwardly against the bottom liner 52. The discharge or trailing end of the slide contact plate 66 extends substantially to the discharge end of the guide channel 20, in close proximity to the plane of cutting of the circular saw 44. In addition, the pressure plate 66 is formed with an upwardly extending side lip 76 along the right hand edge of the presser plate, as viewed in Figures 3 and 4. This longitudinal side lip 76 has at least two functions. It affords a fixed right-hand banking surface and stop for the presser plate 66, operative to engage the adjacent upper vertical side surface 30' of the knife block 30, as seen in Figure 3. Without this side lip 76, the plate 66 would have no banking surface to the right, and might possibly be displaced an excessive distance to the right, sufficient to shear or tear the neoprene layer 64. Also, slugs being ejected through the knife block might otherwise force plate 66 to the right a sufficient distance to permit the slugs to be caught between the left-hand edge of plate 66 and the vertical face 28 of the vise-frame 26. The addition of the side lip 76 extends the control or presser plate 66 upward enough to provide a fixed right-hand stop for the presser plate, which avoids the above difficulties. The side lip 76 also functions to strengthen the control plate 66.

As will be seen from Figures 3 and 4, the left hand edge of the presser plate 66 is disposed in close proximity to the vertical side wall 28 of the vise frame 26, so that it is impossible for the upper edge of a type slug S to become caught between the presser plate and this side wall. The presser plate is made wider than the maximum thickness of type slug S which can be cast in the linecasting machine, whereby the right hand edge of the presser plate 66 overlies the spring plate 34 and the adjacent edge of the knife block 30.

To illustrate the difference in thicknesses or widths of the type slugs passing under the controlling influence of my improved control guide 60, in Figure 7 I have illustrated a conventional type slug, designated S1, having an over-all standard thickness established by the line casting machine; and in Figure 8 I have illustrated a composite type slug assembly, designated S2, characterized by overhanging type characters. In the conventional slug S1 of Figure 7, the small letters, capital letters, numerals, etc. do not extend beyond the side edges of the slug body. In the composite assembly S2 of Figure 8, the main slug S3 (Figure 8A) has overhanging type characters S4, which are shown as having an extent of overhang corresponding to the thickness of two standard slug bodies, although this degree of overhang may be made greater or lesser, as desired. These overhanging characters are backed up or supported by underbuilding or secondary back-up slugs S5, S6, etc., of which there may be one, two or more, depending upon the extent of overhang of the overhanging characters S4. These secondary or underbuilding slugs may have plain front-edge surfaces, devoid of any type characters thereon, as exemplified by the plain secondary slug S5 of Figure 8B. On the other hand, these secondary slugs may have type characters S7, such as are shown on the secondary slug S6 of Figure 8C, which type characters S7 are spaced to land between or beyond the overhanging type characters S4, as for completing the context begun by the overhanging characters S4. These overhanging type characters S4 are used frequently in making up grocery store advertisements and the like.

Although every slug should be trimmed on both sides to make it parallel, it has never been possible to trim the lower side of a slug carrying overhanging characters, such as the slugs S3. An operator opens the knife block

30 wide enough to pass the slug S3 with the overhanging characters S4. And he leaves it open for the solid slugs S5 and S6 to be used with the master slug S3 of the set. By doing this, the solid slugs S5 and S6, as well as the master slug S3, are not trimmed. Leaving the knife block 30 open in this manner is, of course, frowned upon, yet it has become almost universal actual practice.

Because of its irregular configuration, the odd-shaped slug S3 with the overhanging characters S4 is much more likely to twist in the knife block than the solid slug.

The solid slugs, lacking the side-pressure of the spring plate 34, as intended are also more likely to twist in the knife block.

Once a slug twists along its vertical axis in the knife block, the ejector blade 16 slips alongside it, and the slug is not ejected. Oftentimes the operator does not notice this and sends in a second slug, with the result that a slug jam-up in the knife block occurs, necessitating the bothersome job of removing the jam.

20 My improved slug control guide 60 prevents such jam-ups on both types of slug—viz the slugs S3 with overhanging characters, and the solid slugs. By its diagonal down-pressure this control guide 60 presses the slug against the vise frame so that it cannot twist and allow the ejector blade 16 to slip by alongside it.

With regard to this improved slug guiding control, attention is directed to the fact that the uniform thickness and uniform resiliency of the neoprene pad 64 from end to end thereof results in a uniform downward pressure being exerted by the presser plate 66 against the upper end of each type slug S1, S3, S5, S6, etc. throughout the full line of travel of the type slug through the guide channel 20. Still further, the transverse compressibility of the neoprene pad 64 enables the relatively wide presser plate 66 to cock laterally downwardly in its guiding engagement with each type slug (Figures 3 and 4), thereby bringing the above described lateral component of pressure to bear diagonally against the upper right hand edge of the type slug for holding the type slug 40 pressed laterally against the vertical wall 28 of the vise frame 26. As previously described, this diagonally downward and inward component of pressure holds each type slug pressed to the left against the face 28 of the vise frame 26, so as to prevent the ejector blade 16 from slipping alongside the slug, between the vise frame and slug. Such lateral component of pressure occurs irrespective of the width or thickness of the type slug, owing to the relatively wide transverse span of the neoprene pad 64 and presser plate 66. It will be seen 45 from the foregoing that the elastomeric or neoprene pad 64 establishes a resilient full-floating mounting for the presser plate 66, which permits universal tilting movement of this presser plate relatively to the slug guiding channel 20, i.e. it permits tilting movement of the presser plate 66 in the fore and aft dimension of the slug guiding channel 20, and it also permits tilting movement of the presser plate 66 in the transverse dimension of the slug guiding channel 20. The downward and inward component of pressure of the control guide is especially 50 helpful in controlling the slugs S3 carrying the overhanging type characters S4 shown in Figure 8A. Thus, my improved control guide automatically adjusts itself to the guidance of conventional solid slugs S1, or slugs S3 with overhanging characters S4, regardless of the 55 thickness of the conventional slugs or the width of the overhanging characters S4.

Still further, the rubber resilient or neoprene composition of the cushioning pad 64 is not subject to the crystallizing and fatiguing characteristic of metals, and hence 60 has a very long life.

I wish it to be understood that while my improved slug control guide 60 has its maximum utility in a Linotype, Intertype or other linecasting machine which is equipped with a Mohr slug cutting saw, nevertheless this 75 slug control guide can also be used to advantage in such

a linecasting machine (preferably producing the same type of composition) which is not equipped with a Mohr saw.

While I have illustrated and described what I regard to be the preferred embodiment of my invention, nevertheless it will be understood that such is merely exemplary and that numerous modifications and rearrangements may be made therein without departing from the essence of the invention.

I claim:

1. In slug sawing apparatus for use in connection with a linecasting machine embodying a slug cutting saw and a slug guiding channel for guiding the cast type slugs from the mold wheel of the linecasting machine to the slug cutting saw, the combination therewith of a control guide extending along one edge of said slug guiding channel and remaining in slug guiding relation to said channel independently of the rotation of said mold wheel, said control guide comprising a presser plate adapted to engage one end of each type slug, and an elastomeric backing for holding said presser plate resiliently pressed with a floating mounting against the end of the type slug as it travels along said guide channel, the floating mounting afforded by said elastomeric backing permitting edgewise tilting of said presser plate.

2. In slug sawing apparatus for use in connection with a linecasting machine embodying a slug guiding channel for guiding the cast type slugs from the mold wheel of the linecasting machine, the combination therewith of a control guide extending along the upper edge of said slug guiding channel and remaining in said channel independently of rotation of said mold wheel, said control guide comprising a presser plate adapted to engage the upper end of each type slug, and a neoprene pad above said presser plate for holding said presser plate resiliently pressed downwardly with a full-floating mounting against the upper end of each type slug as it travels through said guide channel, the full-floating mounting afforded by said neoprene pad permitting edgewise tilting of said presser plate in a direction transverse of said slug guiding channel.

3. In slug sawing apparatus for use in connection with a linecasting machine embodying a slug guiding channel for guiding the cast type slugs from the mold wheel of the linecasting machine, the combination therewith of a control guide extending along the upper edge of said slug guiding channel, said control guide comprising an upper mounting plate, an intermediate pad of elastomeric material and a lower presser plate, and all remaining in slug guiding position in said channel independently of rotation of said mold wheel said intermediate pad being secured to said upper mounting plate and to said lower presser plate, said intermediate pad of elastomeric material serving to hold said presser plate pressed resiliently downwardly against the upper end of each type slug as it travels along said guide channel.

4. In a slug control guide of the class described, for use in connection with a linecasting machine embodying a vise frame and a knife block defining therebetween a slug guiding channel for guiding the cast type slugs from the mold wheel of the linecasting machine, the combination therewith of a slug control guide independent of said mold wheel extending along the upper edge of said slug guiding channel, said slug control guide comprising an upper mounting plate, an intermediate pad of elastomeric material and a lower presser plate all secured together, said presser plate having an upwardly curved end portion at the entrance end of said slug guiding channel to guide the upper ends of the type slugs under the presser plate, and said intermediate pad of elastomeric material affording a floating compressible mounting for said lower presser plate permitting tilting movement of said presser plate in a direction extending transversely of said slug guiding channel so as to cause said presser plate to exert a diagonally downward and inward pres-

sure against the upper ends of the type slugs as they travel through said slug guiding channel so as to hold said slugs pressed laterally against said vise frame.

5. In a slug control guide of the class described, for use in connection with a linecasting machine embodying a vise frame and a knife block defining therebetween a slug guiding channel for guiding the cast type slugs from the mold wheel of the linecasting machine, and a guide support block extending along the upper edge of said slug guiding channel, the combination therewith of a slug control guide independent of said mold wheel and comprising an upper mounting plate, an intermediate pad of elastomeric material and a lower presser plate, a mounting flange bent upwardly at one end of said mounting plate, and a mounting screw passing through said mounting flange and engaging in said guide support block, said presser plate having an upwardly curved end portion at the entrance end of said slug guiding channel to guide the upper ends of the type slugs under the presser plate, and said intermediate pad of elastomeric material being secured to said mounting plate and to said presser plate and affording a full-floating resilient mounting for said presser plate permitting tilting movement of said presser plate in directions extending both transversely and fore and aft of said slug guiding channel so as to cause said presser plate to exert a diagonally downward and inward pressure against the upper ends of the type slugs as they pass through said slug guiding channel so as to hold said slugs pressed laterally against said vise frame.

6. In a slug control guide of the class described, for use in connection with a linecasting machine embodying a vise frame and a knife block defining therebetween a slug guiding channel for guiding the cast type slugs from the mold wheel of the linecasting machine, the combination therewith of a slug control guide independent of said mold wheel extending along the upper edge of said slug guiding channel, said slug control guide comprising an upper mounting plate, an intermediate pad of elastomeric material and a lower presser plate all secured together, said lower presser plate having a transverse width wider than the maximum thickness of type slug which can be cast in said linecasting machine, said intermediate pad of elastomeric material affording a floating resilient mounting for said lower presser plate permitting tilting movement of said presser plate in a direction extending transversely of said slug guiding channel so as to cause said presser plate to exert a diagonally downward and inward pressure against the upper ends of the type slugs as they travel through said slug guiding channel so as to hold the slugs pressed laterally against said vise frame, and a side lip stop extending upwardly from that edge of said presser plate adjacent to said knife block and operative to engage said knife block for limiting sidewise shifting of said presser plate.

55. In slug sawing apparatus for use in connection with a linecasting machine embodying a slug guiding channel for guiding the cast type slugs from the mold wheel of the linecasting machine, the combination therewith of a control guide extending along the upper edge of said slug guiding channel and remaining in position in said channel independently of the rotation of said mold wheel, said control guide comprising a guide plate adapted to engage the upper ends of the type slugs, and yieldable means for holding said guide plate pressed resiliently downwardly against the upper ends of the type slugs as they travel through said slug guiding channel.

8. In a slug control guide of the class described for a linecasting machine embodying a vise frame and a knife block defining therebetween a slug guiding channel for guiding the cast type slugs from the mold wheel of the linecasting machine, the combination therewith of a control guide independent of said mold wheel extending along the upper edge of the slug guiding channel, said control guide comprising a guide plate adapted to engage the upper ends of the type slugs and yieldable means

for holding said guide plate pressed resiliently downwardly against said type slugs as they travel through said slug guiding channel.

9. In a slug control guide of the class described for a linecasting machine embodying a vise frame and a knife block defining therebetween a slug guiding channel for guiding the cast type slugs from the mold wheel of the linecasting machine, the combination therewith of a control guide independent of said mold wheel extending along the upper edge of the slug guiding channel, said control guide comprising a presser plate adapted to engage

one end of each type slug, and an elastomeric backing for holding said presser plate pressed resiliently downwardly against the end of the type slug as it travels along said guide channel.
